(57) **ABSTRACT**

The buoyancy control device for scuba diving comprises an air bladder, a harness comprising at least two shoulder straps and an abdominal strap made up of two abdominal half-straps, a backrest provided with first slots engaged by the abdominal half-straps, second slots engaged by at least one retaining strap for retaining at least one air cylinder, one or more third slots engaged by the two shoulder straps, and one or more fourth slots engaged by corresponding straps for connecting the backrest to the air bladder.

FIG. 1

FIG.2

FIG.3

FIG.4

FIG.4b

1
BUOYANCY CONTROL DEVICE FOR
SCUBA DIVING

CROSS REFERENCE TO RELATED
 APPLICATIONS

This application claims benefit of priority to Italian Patent Application No. 102021000028802, filed Nov. 12, 2021, the entire contents of which are hereby incorporated by reference.

FIELD

The present invention relates to a buoyancy control device for scuba diving.

BACKGROUND

Buoyancy control devices (BCD) have been known and present on the market for some time as individual accessories for scuba diving used to increase the diver's ability to control the level of depth to be maintained or varied during a dive.

A BCD comprises an air bladder, a harness and a backrest which enables the assembly between the cylinder(s), the harness and the air bladder.

The expandable air bladder, generally made of synthetic materials, is inflated with air coming from the cylinder(s), and the volume thereof is regulated by inflation and deflation valves directly controlled by the diver: the increase or decrease in volume has a direct effect on hydrostatic thrust and therefore helps the diver to maintain or reach the hydrostatic balance required and desired at the various diving depths.

The harness normally comprises two adjustable shoulder straps, an adjustable abdominal strap enabling the device to be secured in the belly area, and an adjustable chest strap enabling a distribution of weight from the shoulders to the chest area.

The backrest, generally rigid, has an internal plate provided with various slots for adjusting the harness and a shaped area for lumbar support, and an external plate provided with a shaped area for supporting and constraining the cylinder(s).

The rigid backrest is fixed directly to the air bladder in various ways, normally by means of bolts which join the internal plate to the external plate by passing through holes in the air bladder.

One of the problems that may be found in the known backrest fixing systems consists in the fact that it transfers the weight of the cylinder(s) to the air bladder, thus generating intense mechanical stresses on the air bladder which may compromise the structural integrity thereof over time.

Another problem tied to a traditional backrest is related to its excessive weight and bulk, which may penalise the wearing comfort of the BCD for the diver and complicate packing of the BCD in backpacks or suitcases for transport.

SUMMARY

The technical task of the present invention is thus to provide a buoyancy control device for scuba diving which enables the aforesaid technical drawbacks of the prior art to be eliminated.

Within the scope of this technical task, one object of the invention is to provide a buoyancy control device for scuba

2

diving that is robust and resistant, lightweight, comfortable to wear and practical to pack.

The technical task, as well as these and other objects, are achieved according to the present invention by providing a buoyancy control device for scuba diving comprising an air bladder, a harness comprising at least two shoulder straps and an abdominal strap made up of two abdominal half-straps, a backrest provided with first slots engaged by said abdominal half-straps, second slots engaged by at least one retaining strap for retaining at least one air cylinder, and one or more third slots engaged by said two shoulder straps, characterised in that said backrest comprises one or more fourth slots engaged by corresponding straps for connecting said backrest to said air bladder.

15 In one embodiment of the invention, said connecting straps support said backrest floatingly with respect to said air bladder.

20 In one embodiment of the invention, said connecting straps are fastened by stitches to said air bladder.

25 In one embodiment of the invention, said connecting straps are flexible.

30 In one embodiment of the invention, each connecting strap is removably engaged in a fourth corresponding slot.

35 In one embodiment of the invention, at least one connecting strap has an end with a double lip engaged in a fourth corresponding slot.

40 In one embodiment of the invention, said backrest is positioned through a through opening of said air bladder.

30 In one embodiment of the invention, one or more connecting straps are fixed along the perimeter of said through opening.

45 In one embodiment of the invention, said backrest has a fifth slot engaged by a crotch strap.

35 Advantageously, the backrest, not being rigidly connected to the air bladder, is able to transfer the mechanical stresses due to the weight of the cylinder(s) directly to the shoulder straps and abdominal strap, thereby relieving the strain on the air bladder, which can thus maintain its structural integrity for a long time.

BRIEF DESCRIPTION OF THE DRAWINGS

Additional features and advantages of the invention will 45 be more apparent from the description of a preferred, but not exclusive embodiment of a buoyancy control device for scuba diving according to the invention, illustrated by way of non-limiting example in the appended drawings, in which:

50 FIG. 1 shows an overall internal view of the buoyancy control device;

FIG. 2 shows an overall external view, relative to the diver's body, of the buoyancy control device;

FIG. 3 shows an internal view, relative to the diver's body, 55 of the backrest and the coupling thereof with the BCD;

FIG. 4 shows a front view of the backrest;

FIG. 4b shows a rear view of the backrest;

FIG. 5 shows the backrest during the step of fixing to the air bladder.

DETAILED DESCRIPTION

With reference to the aforementioned figures, they show a buoyancy control device denoted in its entirety by the 65 reference number 1.

The buoyancy control device 1 substantially comprises a variable volume air chamber or air bladder 10, a harness 20

enabling the BCD to be worn on the diver's body, and a backrest 100 for fixing and supporting at least one air cylinder.

The harness 20 comprises at least two shoulder straps 21 and an abdominal strap made up of two abdominal half-straps 22, as well as, optionally, a crotch strap 171.

The backrest 100 is a mechanical component intended to support the cylinder, or also two cylinders, and secure them to the back of the diver's body and it must thus be particularly robust and offer suitable mechanical characteristics and characteristics of comfort and constraint, consistent with the function to which it is dedicated; it is typically made with a rigid aluminium or technopolymer body.

The backrest 100 extends prevalently along a longitudinal axis L oriented in the direction of the diver's spinal column when the device is worn.

The backrest 100 extends with an upper portion of narrower width and a lower portion with lateral wings.

The backrest 100 is provided with first slots 110 engaged by the abdominal half-straps 22, second slots 120 engaged by at least one retaining strap 121 for retaining at least one air cylinder and one or more third slots 130 engaged by the two shoulder straps 21.

Advantageously, according to the present invention, the backrest 100 comprises one or more fourth slots 140, 141, 142 engaged by corresponding straps 150, 151, 152 for connecting the backrest 100 to the air bladder 10.

Advantageously the connecting straps 150, 151, 152 support the backrest 100 floatingly with respect to the air bladder 10.

The connecting straps 150, 151, 152 are fastened by stitches to the air bladder 10.

The connecting straps 150, 151, 152 are advantageously flexible.

Each connecting strap 150, 151, 152 advantageously removably engages in a fourth corresponding slot 140, 141, 142.

At least one connecting strap 150, 151 has an end with a double lip engaged in a fourth corresponding slot 140, 141.

In particular, the connecting straps 150, 151 have an end with a double lip engaged in the fourth corresponding slot 140, 141 whilst each connecting strap 152 has a hook-and-loop fastening system for connecting to the corresponding fourth slot 142.

In order to connect each connecting strap 150, 151 to the corresponding fourth slot 140, 141, one lip is folded back and in sequence the front lip and then the folded back one are introduced by pressing them through the slot. The advantage, as noted, is that the connection is not permanent, and the connecting strap can be disengaged from and reengaged to the slot when necessary.

The backrest 100 is positioned through a through opening 160 of the air bladder 10.

One or more connecting straps 150, 151 are fixed along the perimeter of the through opening 160.

In particular, the through opening 160 has a quadrangular shape with two connecting straps 151 positioned on two lateral perimeter sides of the through opening 160 and a connecting strap 150 positioned on an upper perimeter side of the through opening 160.

The backrest 100 may also have a fifth slot 170 engaged by a crotch strap 171.

In practical terms, with reference to the longitudinal axis L of the backrest 100, the first slots 110 extend at least prevalently in the direction of the axis L along the lower lateral wings of the backrest 100, the third slot 130 extends transversely to the axis L adjacent to an upper perimeter side

of the backrest 100, the fifth slot 170 extends transversely to the axis L adjacent to a lower perimeter side of the backrest 100, the second slots 120 extend at least prevalently in the direction of the axis L in an intermediate position between the third slot 130 and the fifth slot 170, the fourth slot 140 extends transversely to the axis L in a position interposed between the second slots 120 and the third slot 130, the fourth slots 141 extend at least prevalently in the direction of the axis L, in an internal position, each adjacent to a corresponding first slot 110, and the fourth slots 142 extend at least prevalently in the direction of the axis L in a position interposed between the third slot 130 and the fourth slot 140.

As mentioned, said backrest 100 is floating with respect to the air bladder 10, being partially housed inside the through opening 160 on the back of the air bladder 10, thus having a portion of the outer face directly on the outside of the device 1 for supporting and fixing at least one air cylinder.

The operation of the buoyancy control device 1 for scuba diving according to the invention appears clear from what is described and illustrated and, in particular, is substantially the following.

The user/diver positions the first cylinder against the outer portion of the backrest 100 configured to directly support the cylinder and secures it with the retaining strap 121.

He or she proceeds in a similar manner in the event of positioning a second cylinder, independently supported and constrained in a position alongside and parallel to the first cylinder.

The user/diver dons the device 1.

The weight of the cylinder, or cylinders, constrained as described above to the backrest 100 not rigidly connected to the air bladder 1, but rather floatingly fixed by the connecting straps 150, 151, 152, is directly transferred from the backrest 100 to the shoulder straps 21.

The mechanical stresses due to the weight of the cylinder(s) are thus directly transferred to the shoulder straps 21, completely relieving the strain on the air bladder 10, which can thus maintain its structural integrity for a long time.

The user/diver completes the donning of the device 1 with the reciprocal engagement and closure of the two abdominal half-straps 22, and the engagement, adjustment and closure of all the known elements provided on the harness.

Advantageously, the reduced size of the backrest 100, the only rigid element of the entire device 1, which is made with substantially flexible materials, facilitates the folding and packing of the entire device, thus facilitating the transport thereof in situations of travel of the user/diver and/or shipment.

In order to improve the convenience of using the buoyancy control device 1, the backrest can have, on the front and back sides thereof, protuberances 200 made of non-slip material, for example obtained from a rubber material co-moulded with the backrest or applied on the backrest, which on the one hand help to keep the cylinder in position against the backrest, and on the other hand help to maintain the backrest comfortably in position against the diver's back.

It has been ascertained in practice that a buoyancy control device 1 according to the invention is particularly advantageous, since it is robust and resistant, long-lasting, lightweight, comfortable to wear and practical to pack.

A buoyancy control device thus conceived is susceptible of numerous modifications and variants, all falling within the scope of the inventive concept as defined in the claims; furthermore, all of the details are replaceable by technically equivalent elements.

5

The materials used, as well as the dimensions, may in practice be any whatsoever, according to needs and the state of the art.

What is claimed is:

1. A buoyancy control device for scuba diving comprising:
an air bladder having a through opening,
a harness comprising:
at least two shoulder straps,
an abdominal strap made up of two abdominal half-
straps, and
connecting straps independent from the shoulder straps
and the abdominal strap,
a rigid backrest positioned through said through opening
and comprising:
first slots engaged by said abdominal half-straps,
second slots engaged by at least one retaining strap
retaining at least one air cylinder,
one or more third slots engaged by said two shoulder
straps,
one or more fourth slots engaged by said connecting
straps connecting said backrest directly to said air
bladder, said one or more fourth slots being slots
passing through the thickness of said rigid backrest,
and
wherein at least one of said connecting straps has a first
terminal end with a double lip engaged in the corre-

6

sponding fourth slot and a second terminal end fixed to the air bladder, said first terminal end facing a front side of the rigid backrest and said second terminal end facing a rear side of said backrest.

2. The buoyancy control device for scuba diving according to claim 1, wherein said connecting straps support said backrest floatingly with respect to said air bladder.
3. The buoyancy control device for scuba diving according to claim 1, wherein said connecting straps are fastened by stitches to said air bladder.
4. The buoyancy control device for scuba diving according to claim 1, wherein said connecting straps are flexible.
5. The buoyancy control device for scuba diving according to claim 1, wherein each connecting strap is removably engaged in a fourth corresponding slot.
6. The buoyancy control device for scuba diving according to claim 1, wherein said one or more connecting straps are fixed along the perimeter of said through opening.
7. The buoyancy control device for scuba diving according to claim 1, wherein said backrest has a fifth slot engaged by a crotch strap.
8. The buoyancy control device for scuba diving according to claim 7, wherein said backrest is formed from a rigid body made of aluminium or technopolymer material.
